UNITED STATES PATENT OFFICE

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS

WASHING MACHINE

Application filed March 5, 1928. Serial No. 259,345.

This invention has reference to washing machines and more particularly to machines intended for domestic use, and it has for its principal object to improve the supporting structure for the tub of such machines and incidentally the wringer column and the transmission case.

The invention has for a further object to improve the supporting structure for the tub of washing machines, particularly where the metallic tub has applied to one or both surfaces thereof a vitreous enamel.

In machines employing metallic tubs, the surfaces of which are covered with vitreous enamel, it is obvious that the legs or standards supporting the tub and incidentally the wringer column and the transmission case, must be secured to the tub at points above the normal water line of the tub and preferably adjoining the upper edge of the tub to avoid checking the enamel at points where leaking would naturally result.

Other and further objects will more fully appear from the following description.

That the invention may be more fully understood, reference is had to the accompanying drawings forming part of this description, illustrating a preferred embodiment of the invention, in which:

Fig. 1 is a perspective view of a well known type of washing machine, the inner and outer surfaces of which have applied thereto a vitreous enamel and including a supporting structure embodying my invention;

Fig. 2 is a detail plan in section, as the same would appear if taken on the line 2—2 Fig. 1;

Fig. 3 is a detail plan in section, as the same would appear if taken on the line 3—3 Fig. 1;

Fig. 4 is a detail perspective view, partly in section, as the same would appear if taken on the line 4—4 Fig. 1;

Fig. 5 is a vertical sectional detail view, as the same would appear if taken on the line 5—5 Fig. 1;

Fig. 6 is a view somewhat similar to Fig. 2, except of a modified structure, and

Fig. 7 is a view similar to Fig. 5 but showing a modification of the structure thereof.

Like characters of reference denote corre-

sponding parts throughout the several figures.

In the drawings, the tub 1, which is preferably shown square has vitreous enamel applied to its inner and outer surfaces *a*, *b*. To the upper open edge of the tub is arranged for attachment a head frame 2, the same having a central opening, not shown, adapted to be covered by the hinged cover plate 3.

Legs or standards 4 support the tub at its four corners, as shown; one of such legs or standards, preferably the one at that corner of the tub coincident with the wringer column 5, comprising separate sections 4*a*, 4*b*, the latter being off-set from the former sections, so as to be coincident or disposed in axial alignment with the column 5 and forming in effect a continuation thereof, the said column 5 and the leg or standard section 4*b* having attachment with upper and lower sections 6 and 7 respectively, of a transmission case 8, and the said leg or standard section 4*a* having attachment with the tub and the upper section 6 of the transmission case 6, being spaced from and lying parallel alongside the column 5. The legs or standards 4 and the lower section 4*b* of the sectional leg or standard have attachment with and support a base plate 9, and to the said legs or standards 4 and to the said leg or standard section 4*b* are secured 80 tubular bearing members 10 through which are adjustably carried caster legs 11, to the lower ends of which are connected swiveled caster wheels 12. The said legs or standards 4 and the said leg or standard section 4*a* are 85 angular in shape, see Figs. 1, 3, 4 and 5 so as to embrace or overlap two sides of the tub, at the respective corners, and such shape form a partial enclosure for the caster legs 11, as shown.

The upper section 6 of the transmission case 8 is formed with or has connected therewith an angularly shaped casting or bracket 13 to which is secured the lower end of the leg or standard section 4*a*, see Figs. 1 and 3, and the lower section 7 of the transmission case 8 is formed with or has connected therewith an angularly shaped casting or bracket 14 to which is secured the upper end of the leg or standard 4*b*, see Figs. 1 and 4.

The transmission case 8, as shown, extends radially outward from on or about the axis of the tub to a corner of the tub to allow for the connections with the upper and lower sections 6 and 7, above described, and the inner end of said transmission case has extending upwardly therefrom a suitable bearing and vertical agitator driving shaft, not shown, which is disposed axially of and within the tub and associated therewith is a suitable water-seal, not shown, common in devices of this character.

To the upper end of the column 5 is swingably attached a wringer support 15 carrying the usual wringer mechanism 16, the actuating means of which is adapted to be driven by a shaft 17, see Fig. 2, housed within the column 5 and adapted to receive its power from driving means, not shown, housed within the transmission case 8.

The head frame 2 is formed or provided with the off-set upwardly extending flange 18, see Figs. 5 and 7, which overlies the upper edge of the tub, and at the corners of the tub overlies the upper ends of the legs or standards 4 and the said leg or standard section 4a, and said head frame is further formed or provided with the inset depending flange 19, see Figs. 5 and 7 which is disposed within the tub and lies next adjacent the inside face of the wall of the tub, as shown.

In Fig. 5 the flange 19 is of a depth to permit of securement of the legs or standards 4 and the said leg or standard section 4a to the wall of the tub and the said flange 19 by rivets or equivalent securing means 20. In Fig. 7 this flange 19 is somewhat shallower and therefore the securing means 20 passes only through the leg or standard 4 and the wall of the tub. These securing means, as will appear, are all above the normal water line in the tub and even though checking of the enamel should occur at these points it will not be material, as no packing will be required as there is no chance of leak. The tub is preferably of pressed steel capable of having applied thereto the vitreous enamel surface or surfaces, but minus the usual depending lugs or brackets to which the legs or standards are usually secured to, and therefore such legs or standards are shaped to provide rather extended surface bracing portions and secured to the tub above the normal water line. Brazing or welding leg or standard securing lugs or brackets to the tub body is not at all practical when applying vitreous enamel surfaces thereto, as will be understood by those skilled in the art.

At the wringer column corner of the tub a bearing bracket 21 is secured to receive the upper end of the column 5 and said bracket 21 is secured direct to the flange 18 of the head frame 2 and at this point the said head frame 2 is provided with strengthening ribs

2' to brace the flange 18 against the lateral and torsional strains arising from the different positions into which the wringer frame 15 may be swung. In Fig. 6 I have shown that instead of securing the bracket 21 to the flange 18 of the head frame 2 this connection may, if desired, be made through the leg or standard section 4a, the wall of the tub and the flange 19 of the head frame.

What I claim is:—

1. In combination, a metal tub, metal legs supporting said tub and having extending bearing surface portions embracing the sides of the tub and extending adjacent to the upper edge of the tub, a head frame having an off-set upwardly extending flange in substantially the vertical plane of the side walls of the tub and overlying the upper edges of the legs and having an inset depending flange within the tub next adjacent the walls of the tub, and a common means securing said inset flange to the walls of the tub and the legs to said tub body.

2. In combination, a metal tub, metal legs supporting said tub and having extending bearing surface portions embracing the sides of the tub and extending adjacent to the upper edge of the tub, a head frame having an off-set upwardly extending flange in substantially the vertical plane of the side walls of the tub and overlying the upper edges of the legs and having an inset depending flange within the tub next adjacent the walls of the tub, a common means securing said inset flange to the walls of the tub and the legs to said tub body, and a base plate connecting and bracing the lower ends of the legs.

3. In combination with a tub and legs having upper portions engaged with the outer side face of the tub and terminating substantially at the top edge of the tub, a head frame mounted on the upper end of the tub and having a laterally offset upwardly extending flange and an inset depending flange engaged with the inner side face of the tub, said offset flange having its outer side face disposed substantially flush with the outer faces of the said upper portions of the legs and having a bottom edge disposed in close proximity to the said upper terminals of the legs, and means to secure the legs to the tub near said head frame.

4. In combination, with a metallic tub, of metallic legs supporting the tub, a transmission case comprising upper and lower sections disposed beneath the tub and extending outwardly from and connected with the center of said tub and intersecting a leg, said last mentioned leg comprising an upper section embracing and secured to the tube and a lower section off-set vertically in relation to the upper section, a connecting means between said upper case section and the lower end of the upper leg section, a connecting means between said lower case section and the upper end

of the lower leg section, a column having its lower end secured to the upper case section in vertical alignment with the lower leg section so as to form a continuation thereof, and means rigidly connecting the column and tub adjacent the upper end of the latter.

5. In combination with a metallic tub, of metallic legs supporting the tub, a transmission case comprising upper and lower sections disposed beneath the tub and extending outwardly from the center of the tub and intersecting a leg, said last mentioned leg comprising an upper section which is engaged over the outer face of the tub and which extends 10 to adjacent the top of the tub and is rigidly connected to the tub at its upper end and a lower section offset vertically in relation to the upper leg section, connecting means between the upper case section and the lower 15 end of the upper leg section and substantially alined with the latter, and connecting means between the lower case section and the upper end of the lower leg section.

In witness whereof, I have hereunto affixed
25 my hand this 25th day of February, 1928.

ALPHEUS W. ALTORFER.
